FLUID MOTOR

Birger Hefty, Tampico, Mex.

Original application March 20, 1935, Serial No. 12,098. Divided and this application June 3, 1935, Serial No. 24,724

3 Claims. (Cl. 121—164)

This invention relates to a fluid motor for pumps, the general object of the invention being to provide a motor operated by fluid and in such a manner that it is entirely automatic and one which can be used in a well for operating a pump piston which is used to lift liquid from the well.

The present invention is a division of application Serial No. 12,098 filed by me on March 20, 1935.

10 This invention also consists in certain other features of construction and in the combination and arrangement of several parts, to be hereinafter fully described, illustrated in the accompanying drawings and specifically pointed 15 out in the appended claims.

10 In describing the invention in detail, reference will be had to the accompanying drawings wherein like characters denote like or corresponding parts throughout the several views, and in 20 which:—

Figure 1 is a vertical sectional view through a well casing showing the motor in use therein for operating a pump piston.

Figure 2 is a longitudinal sectional view through 25 that part of the casing which contains the motor with parts of the motor in section, this view showing the piston of the motor in an intermediate position.

Figure 3 is a similar view but showing the piston 30 in its upper position.

Figure 4 is a view similar to Figure 3 taken a quarter turn therefrom.

Figure 5 is a longitudinal sectional view through the upper portion of the casing shown 35 in Figure 1.

Figure 6 is a section on the line 6—6 of Figure 5.

Figure 7 is a section on the line 7—7 of Figure 2.

40 Figure 8 is a section on the line 8—8 of Figure 4.

Figure 9 is a section on the line 9—9 of Figure 3.

Figure 10 is a view of the two tubular valve 45 members.

Figure 11 is a longitudinal sectional view through the upper end of the discharge pipe.

Figure 12 is a view of one of the spring compressing members.

50 Figure 13 is a view of one of the latch members.

In these drawings, the letter A indicates the well casing which is formed of a plurality of sections threadedly connected together, the lower end of the casing being reduced and the lower

part of the casing extending into the fluid to be pumped. The upper end of the casing is also reduced and a discharge pipe 1 is connected to the upper part of this reduced portion for leading the fluid to a tank or the like. A pipe line, 5 a part of which is shown at 2, leads from a pump, compressor or other source of fluid under pressure, through a plug 3 closing the top of the reduced upper portion of the casing into the upper portion of the wide part of the casing where the 10 lower end of this part 2 is threaded into a stationary plug 4 which is supported in the casing in any suitable manner such as having an annular part clamped between two sections of the casing as shown in Figure 5. The upper end of 15 the plug is formed with a conical recess 5 terminating in a tapered threaded lower end for receiving the threaded tapered end of the part 2 of the pipe line, the conical part 5 acting as guiding means for the lower end of the part 2 20 to facilitate the threading of the lower end of the part 2 in the threaded part of the plug so that the bore of the pipe part 2 will register with the bore 6 of the plug, the lower end of the bore 6 having a threaded enlargement for receiving 25 the upper threaded end of the part 2' of the pipe part. The plug is also provided with the vertically arranged holes 7 for the passage of fluid upwardly through the plug. The upper portion 30 of the part 2' of the pipe line is offset as shown in Fig. 5 so that the lower portion of the part 2' will be located close to a portion of the internal wall of the casing and the lower end of this part 2' is threaded in a vertical passage 8 passing entirely through a plug 9 held stationary in the 35 casing between two of the sections thereof, as shown more particularly in Fig. 2. Thus plug 9 forms a receiving chamber 10 between itself and the plug 4. A third plug 11 is held in a stationary manner between two of the sections of the 40 casing and this plug with the plug 9 forms a chamber 12 for the working or operating piston 13. Another plug 14 is stationary held in the casing between two of the lower sections thereof and this plug forms with the plug 11 a chamber 15 for the pumping piston 16.

A main discharge pipe 17 passes through a vertically arranged bore in the piston 13 and is fastened to the piston by a screw 17' as shown in Fig. 7 though if desired, this pipe 17 may be formed of upper and lower sections, the adjacent ends of which are threaded in the bore of the piston 13. The upper part of the pipe 17 extends into the chamber 10 and has a cage 18 50 threaded to its upper extremity in which is lo- 55

cated a valve 19, the valve being arranged to permit fluid to discharge from the pipe 17 into the chamber 10 but prevents fluid from passing from the chamber 10 back into the pipe. This pipe 17 has a close sliding fit in a vertical hole in the plug 9 and also a sliding close fit in a hole or bore passing through the plug 11, the lower end of said pipe 17 being threaded in the upper end of the pumping piston 16 to receive the liquid discharged by the pump as described in the above mentioned application.

A pair of elongated tubular valve members 33 and 34 are connected together adjacent their ends by the cross bars 35 shown more particularly in Figure 10 and these tubular valve members 33 and 34 pass slidably through vertical bores in the piston 13 and the upper end of the tubular valve 33 has a sliding close fit in the bore 8 of the plug 9 and the upper end of the valve 34 has a sliding close fit in the vertical bore 36 in the plug 9 and located opposite the bore 8. The upper end of the bore 36 discharges into the chamber 10. A vertical chamber 37 is formed in the lower part of the plug 9 and opens out through the bottom of the plug into the chamber 12 and vertically offset ports 38 connect the chamber 37 with intermediate parts of the bores 8 and 36. Ports 39 in the upper ends of the valves 33 and 34 are adapted to register with these ports 38 when said valves 33 and 34 are in different positions. For instance, the port 39 of the valve 33 will register with the upper port 38 when the valves 33 and 34 are in their raised positions but the port 39 of the valve 34 will be out of register with the lower port 38 as shown in Figure 3. Then when the valves 33 and 34 are in lowered position, the port 39 of valve 33 will be out of register with its port 38 while the port 39 of the valve 16 will be in register with its port 38 as shown in Fig. 2 and as the ports 38 are in communication with the chamber 37 which in turn is in communication with the upper end of the chamber 12 of piston 13, these valves 33 and 34 will control the flow of fluid into and from the upper end of the chamber 12.

The lower ends of the valves 33 and 34 extend into vertical bores in the plug 11, the lower ends of these bores being closed and a chamber 40 is formed in the plug 11 and opens out through the upper end of the plug into the chamber 12 and this chamber 40 is provided with the vertically offset ports 41 controlled by the ports 42 in the lower ends of the valves 33 and 34, the ports just described being so arranged that when an upper port of one of the valves 33 and 34 is in communication with a port 38, the port 42 of said valve is out of communication with the port 41 and when a port 42 is in communication with the port 41, a port 39 is out of communication with a port 38 as shown in Figs. 2 and 3.

The piston 13 is formed with a centrally arranged vertical bore 43 in which is located a spring 44 and plugs 45 close the ends of the bore 43 and have rounded heads projecting from the ends of the piston 13. A rod 46 passes slidably through each plug 45 and has a head 47 at its inner end contacting an end of the spring and each rod is so located that it will engage the cross bars 35 as the piston 13 nears the ends of its strokes. A spring-actuated latch 48 is pivoted to each of the plugs 9 and 11, a latch being shown in detail in Fig. 13 and each latch is provided with a shoulder 49 for engaging a cross bar 35 for holding the cross bar and therefore the valves 33

and 34 against movement towards that plug which carries the latch. Thus, as the piston 13 approaches an end of its stroke, a rod 46 will strike a cross bar 35 and as the bar 35 is held against movement by the rod 46 by the latch 48, the rod 46 is pushed inwardly so that its head will compress the spring and this action will continue until the piston reaches a position where a head of the plug 45 will engage the latch 48 and thus move it to releasing position and then the energy stored in the contracted spring 44 will cause the rod 46 to press the cross bar 35 and the valve members 33 and 34 towards the plug, towards which the piston 13 is moving, and thus the valves 33 and 34 will be shifted to another position.

For instance, with the parts shown in Fig. 2, the propulsion fluid from the pipe line 2 will flow through the section 2' into the bore 8 through the valve 33 and pass from the valve through the port 42 at its lower end into the port 41 and through the chamber 40 into the lower part of the chamber 12 so that the piston 13 is forced upwardly and the fluid or liquid in the chamber 12 above the piston 13 will pass therefrom through the chamber 37, right hand port 38 into the upper port 39 of valve 34 and through the bore 36 of plug 9 into the chamber 10. Of course, the fluid entering the bore 8 cannot enter the upper chamber 37 as the left hand port 38 is closed as will be seen in Fig. 2. As the piston 13 nears the upper end of its stroke, the upper rod 46 will strike the upper cross piece 35 which is held against upward movement by the upper latch 48. Thus, the rod 46 will compress the spring 44 as the piston continues its upward movement and then when the head of the upper plug 45 strikes the upper latch 48, the latch will be released from the upper cross bar 35 and the energy stored in the spring will force the upper cross bar 35 and the valves 33 and 34 with the lower cross bar 35 upwardly and thus change the positions of the valves 33 and 34 from that shown in Fig. 2 to that shown in Fig. 3. Then the fluid in section 2' of the pipe line will enter the bore 8 and the upper part of valve 33 and as it cannot escape from the lower end of valve 33, the fluid will pass through the port 39 of valve 33, the upper port 38 in the chamber 37 and then flow from chamber 37 into the upper end of the chamber 12 so that the piston 13 will be moved downwardly. The fluid in the lower part of the chamber 12 will be forced by the downwardly moving piston 13 into the chamber 40 of plug 11 and through the right hand port 41 into the port 42 at the lower end of the valve 34 and then flows upwardly through the valve 34 and escapes from the bore 36 of plug 9 into the chamber 10. Of course, the spring will be compressed as the piston 13 nears the lower end of its stroke, after which the lower latch 48 will be released by the lower plug 45 and then the valves 33 and 34 will be shifted to the position shown in Fig. 2. Thus, the piston 13 is reciprocated by the fluid flowing through the pipe line 2 and its section 2'.

As the piston 13 is reciprocated, it will impart a reciprocatory movement to the discharge pipe 17 and as the lower end of this pipe 17 is connected with the pumping piston 16, then piston 16 will be reciprocated as well as the suction pipe 23, connected to the piston 16.

Thus, it will be seen that the piston 13 is operated by the fluid introduced into the chamber 12 from the pipe line 2 and the reciprocation of this

piston 13 is communicated to the pumping piston 16 so that the liquid or fluid is drawn from the well and discharged into the chamber 10 from which it flows through the upper part of the casing to the discharge pipe 1 which may lead to a tank or the like, the propulsion fluid for the piston 13 also discharging into the chamber 10 and flowing with the liquid from the well into the pipe 1. The main discharge pipe 17 acts as connecting means between the two pistons and the valve 24 permits discharge of fluid under pressure of the well directly into the discharge pipe without interfering with the pumping action of the piston 16 or with said piston interfering with the discharge of the fluid under pressure.

The elongated tubular valves not only act as valves but they also serve as conduits for the fluid and the valves 33 and 34 also act in conjunction with the pipe 17 as guides for the piston 13.

Another advantage of the invention is that no matter how slow it operates, it will never stop at dead center because the tubular distribution valves operate simultaneously and change positions in a snap fashion by means of the triggers and the spring means. Also by using the proper sizes of headed plugs 45, the parts can be adjusted to operate with absolute precision.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. A motor of the class described comprising a cylinder, a piston in the cylinder, a chamber in each end of the cylinder opening out into the cylinder and each end of the cylinder having bores therein and ports connecting the chambers with the bores, means for introducing fluid under pressure into one bore of one end of the cylinder, the other bore of said end forming a discharge, a pair of tubular valve members connected together and

extending through the cylinder and having their ends slidably arranged in the bores of both ends of the cylinder and controlling the ports leading to the chambers and means operated by the piston at each end of its stroke for shifting the valve members for causing the fluid to pass into alternate ends of the cylinder and to discharge from the other alternate ends.

2. A motor of the class described comprising a cylinder having bores at its ends and a chamber 10 in each end opening out into the cylinder, one bore in one end acting as a discharge, means for introducing fluid under pressure into the other bore of said end, a pair of elongated tubular valve members having their ends slidably arranged in 15 the bores and each end having ports therein out of alignment and connecting the chambers with the bores, the ends of said valve members having ports therein for controlling the first mentioned ports, a piston slidably arranged on the valve 20 members, spring-pressed rods projecting from the ends of the piston, cross pieces connecting the valve members together and engaged by the rods at the ends of the strokes of the piston for compressing the spring, latch means at the ends of 25 the cylinder adjacent the cross pieces for preventing movement of the valve members and projections on the ends of the piston for releasing the latch means as the piston nears each end of its stroke.

3. A fluid motor of the class described comprising a cylinder, a piston in the cylinder, means for introducing compressed fluid into one end of the cylinder, said end having a discharge opening, means including a pair of elongated tubular valve 35 members passing through the cylinder and connected together for first introducing the fluid into one end of the cylinder to force the piston in one direction and to exhaust the opposite end of the cylinder and then to introduce the fluid 40 into the opposite end of the cylinder and exhaust the other end and means operated by the piston as the same nears the end of its stroke for reversing the valve members.

BIRGER HEFTYE. 45
